UNITED STATES PATENT OFFICE.

EDWARD A. HEMPHILL, OF JERSEY CITY, NEW JERSEY.

MECHANISM FOR INDEX-MARKING CARDS OR SHEETS.

Application filed July 7, 1922. Serial No. 573,507.

To all whom it may concern:

Be it known that I, EDWARD A. HEMPHILL, a citizen of the United States, residing at Jersey City, in the county of Hudson and State of New Jersey, have made certain new and useful Improvements in Mechanism for Index-Marking Cards or Sheets, of which the following is a specification.

The invention relates to devices for making index indications in cards or sheets, and more particularly to a novel punch and cooperating interchangeable guides for making indexing cuts in cards or sheets.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:—

Fig. 1 is a plan view of one form of the cooperating guides and showing the punch in horizontal section on the line 1—1 of Fig. 6;

Fig. 2 is a view similar to Fig. 1 and showing another of the interchangeable guides in use;

Figs. 3 and 4 are views similar to Fig. 2 but showing different spacing of the indicating marks on the guides and index cards or sheets, to suit the different spacing or positioning of the index cuts in the card;

Fig. 5 is a view similar to the preceding views but showing a different marking on the guides and cards; and

Fig. 6 is an elevation looking at the preceding figures from the left and showing the punch in full elevation.

The invention comprises a punch and operating and interchangeable guides for cutting index marks in the edges of cards or sheets. The punch and plurality of guides are inter-related, so as to make cuts of different depths or sizes and positions, to constitute different indexing significa-

tions, such for example as cuts of different depths to differentiate between classes and sub-classes, and with such different depths of cuts variably positioned along the card to indicate any desired one of a plurality of classes, or any desired one of a plurality of sub-classes. Such an indexed card and indexed card system are shown and described in my copending application Ser. No. 567,060, filed June 9, 1922.

Referring now in detail to the embodiment of the invention, illustrated by way of example in the accompanying drawings, the punch mechanism may be of any suitable or convenient design so far as many of its features are concerned. As embodied, a relatively long and narrow rectangular base 1 is provided for supporting and positioning the cooperating guides and the cards or sheets to be marked. Fixed to the base, centrally and at the rear thereof, is a vertically disposed and preferably rectangular standard or support 2 for the punch mechanism.

In the base 1 is the die member 3 for effecting, with the punch, the index cuts in the cards or sheets, these cuts being preferably made in the edges of the cards or sheets. Cooperating therewith is a punch member 4, vertically reciprocably mounted in guides 5 and 6, fixed to and extending horizontally outwardly from the standard or support 2. The punch and die as shown are adapted to make a V-shaped cut in the edge of the card or sheet.

The punch member is provided with a head or handle 7, and is resiliently held in inoperative position by a helical spring 8, which is seated on the guiding member 6 and is in compression between that member and a washer 9, encircling the punch, and held in place longitudinally by a pin 10, which is fastened in and projects out from the punch 4. The guide 5 coacts with the pin 10 to form a stop for the punch against the pressure of its spring.

In the form of guides shown in Figs. 1 and 2, they are designed to mark the respective months as classes, and the days of the month as sub-classes under the various classes or month. In this embodiment, the cut for the class is appreciably deeper than the cut for the sub-class, this difference in size being an aid to the eye in indicating the arrangement of the cards in the system.

or group. It also serves to bring the respective cuts for the class and sub-class into proper relation with the corresponding markings on the cards or sheets.

5 Thus, for example, the days of the month are printed or otherwise marked in numerical order in a row 11 along the top edge of the card, and the months are arranged in a second row 12 parallel with and just below 10 the days of the month. The cooperation of the cuts of different depths with the corresponding marks on the card will be seen from Fig. 2, which has been marked for January 31. The relation of the system or 15 group of cards to each other as marked for classes and sub-classes will be best seen and understood from my copending application Ser. No. 567,060 already referred to.

In Fig. 1, a guide 15, which may be a flat 20 strip of metal, cardboard, fibre or other suitable material, is brought by suitable means into fixed predetermined relation, both longitudinally and transversely, with the punch and die, and for this purpose, as 25 embodied, is cut away as shown at 16 to fit snugly about the standard 2.

The front edge 17 of this guide is so positioned that when the edge 18 of the card is placed thereagainst, the cut 19 will be of just 30 the desired or required depth to indicate the month or other class of the card. This one guide is adapted to cut all the notches for all the classes, that is, in this case for all the months.

35 Cooperating with the guide 15 (which, as stated, regulates the depth or size of the index cut) is another guide which assists in locating this class-differentiating cut along the card so as to indicate the particular class, 40 which in this present case, is the particular month. This guide, as embodied, consists of a plate or strip 20, mounted upon, extending across, and slidable along the base 1. Guide or slide 20 is held in fixed position 45 by suitable means, such as its two ends 21 and 22, which are bent downward about the front and rear faces on the base 1, as shown in Fig. 6. The guide 20 has a face 23 against which the ends 24 of the cards or sheets are 50 positioned or registered. The guide has also a face 25, which is likewise in register with the class indications or markings 26 on the guide 15, which in this case are the months. Thus the card is brought into 55 longitudinal register with the punch to be marked for the desired month.

In Fig. 1 the guides 15 and 20 are shown in position for punching the index cut for January. It will thus be seen that the 60 month indications for all the months, or other corresponding class indications, for all the classes, may be punched in proper position in the card by the use of one guide 15.

A guide 20^a may be employed, if desired, 65 to hold the right-hand end of the various

guides, and may be like guide 20, except that there is no occasion for moving it along the base.

The guide for positioning the cards or sheets to make the cut or notch for the sub-class, which in the exemplary case would be for the day of the month, and is shallower than the class or month indicating notch, may be generally similar to the guide 15, and such a guide 30 as shown in Fig. 2. 70 The guide 20 cooperates with a guide 30 in the same manner that it cooperates with the guide 15. Guide 30 is shown provided with markings 29 for the days of the month. The card which was notched for the month in Fig. 1 is shown in Fig. 2 being notched for the day of the month, that is, so that by the two notches the card will be marked for January 31.

In Figs. 3 and 4 guides 30^a and 30^b are 85 shown similar to the guide 30, except that the markings 29 for the days of the month are differently spaced on the card or sheet, and the marks 29 correspondingly on the guides, as shown correspondingly at 29^a, 29^b and 29^c and 29^d, so as to avoid their being cut out by the month-indicating or other class-indicating notch.

In Fig. 5 an arrangement of indicating marks is shown on both the card and the 90 guides 30^e whereby the class and sub-class are indicated in a single line upon the card and may be indicated if desired by notches of equal size or depth, placed at different points along the card. If, for purposes of 100 differentiating the class notch and the sub-class notch when the cards are massed in the system or group of cards, it is desired to have the class notch larger or deeper, or vice versa, two guides of different widths 105 can be used, as already explained in connection with the marking of the months and days of the month.

It will be understood that changes may 110 be made from the details of structure and arrangement herein shown and described without departing from the principles of the invention and without sacrificing its chief advantages.

What I claim is:—

1. A mechanism for index marking cards or sheets with a notch in one edge thereof comprising a punch, a guide in predetermined position relatively to the punch for positioning an edge of the cards or sheets to receive an indexing cut of a desired size, and a cooperating and relatively movable guide for variably locating said cut along the card or sheet. 115

2. A mechanism for index marking cards or sheets comprising a punch, a removable guide in predetermined position relatively to the punch for positioning an edge of the cards or sheets to receive an indexing notch of a desired depth, and a cooperating and 120

130

relatively movable guide for variably locating said cut along the card or sheet.

3. A mechanism for index marking cards or sheets comprising a punch, a guide in pre-

5 determined position relatively to the punch for positioning an edge of the cards or sheets to receive an indexing notch of a desired depth, and a cooperating and relatively movable guide for variably locating said 10 cut along the card or sheet, the last named guide being movable perpendicularly to the first-named guide.

4. A mechanism for index marking cards or sheets comprising a punch, interchangeable guides adapted to pass into respective predetermined, but different positions relatively to the punch, for correspondingly variably positioning an edge of the cards or sheets relatively to the punch, to receive 20 indexing cuts therein of corresponding difference in size, and a cooperating guide relatively movable to position the cut along said edge of the card or sheet.

5. A mechanism for index marking cards or sheets comprising a punch, interchangeable guides adapted to pass into respective predetermined, but different positions relatively to the punch, for correspondingly variably positioning an edge of the cards 25 or sheets relatively to the punch, to receive indexing cuts therein of corresponding difference in size, and a cooperating guide relatively movable perpendicularly to the first named guide to position the cut along said 30 edge of the card or sheet.

6. A mechanism for punching an index

card along an edge, comprising a punch, a calibrated guide cooperating with the punch, and a slide movable along the calibrated guide.

7. A mechanism for notching index cards along one edge, comprising a punch, a guide normally fixed in relation to the punch, and a slide, movable along the guide, against which the card is placed, the position of the slide on its guide determining the position of the notch in the card.

8. A mechanism for punching index cards which are provided with class indicating markings along one edge thereof, comprising a punch, a guide normally fixed in relation to the punch, and provided with similar class indicating markings, a slide movable along the guide against which the card is placed, the position of the slide indicating on the guide a marking corresponding to the marking that is to be punched in the card.

9. A mechanism for punching index cards which are provided with class indicating markings along one edge thereof, comprising a punch, a guide normally fixed in relation to the punch, and provided with similar class indicating marks, but which are reversely arranged as compared with the markings on the cards, a slide movable along the guide against which the card is placed, the position of the slide indicating on the guide a marking corresponding to the marking that is to be punched in the card.

In testimony whereof, I have signed my name to this specification.

EDWARD A. HEMPHILL.
